UNITED STATES PATENT OFFICE.

FRANCIS W. DEAN, OF LEXINGTON, MASSACHUSETTS.

FIRE DOOR.

1,408,867.

Specification of Letters Patent.

Patented Mar. 7, 1922.

Application filed August 7, 1919. Serial No. 315,923.

To all whom it may concern:

Be it known that I, FRANCIS W. DEAN, a citizen of the United States of America, a resident of Lexington, in the county of Middlesex, State of Massachusetts, have invented certain new and useful Improvements in Fire Doors, of which the following is a full, clear, and exact description, reference being had to the accompanying drawings, forming 10 a part of this specification.

My invention relates to improvements in fire doors adapted for use on furnaces and the like, the object being to produce a draft receiving fire door whereby the draft is most effectively utilized to facilitate combustion of the fuel, and also to prevent burning away of the inside of the door and the inner margin of the dead plate which lies adjacent to the fuel. To accomplish these results, the draft should be discharged directly into the bed of fuel, instead of being permitted to escape over the top of the fuel bed, and almost the entire area of the inner wall of the fire door should be exposed to 20 the cooling action of all of the draft passing through the door. It is especially important to effectively utilize the draft as a means for cooling the lower margin of said inner wall.

Prior to this invention, fire doors formed 30 with inner and outer walls have usually been provided with a large draft inlet near the center of the outer wall, and the inner wall has been perforated at various points above and below the horizontal center line of the 35 door, to provide numerous scattered discharge openings for the draft. In these old fire doors, the draft, entering at the center of the outer wall of the door, strikes the perforated inner wall which serves as a baffle 40 or distributor, causing the air currents to spread in various directions so as to escape through the numerous perforations above and below the horizontal center line of the door. However, most of the air will escape 45 through the perforations near the center of the door. It will be observed that substantially all of the draft will be discharged entirely above the top of the bed of fuel in the furnace, but the draft would be far more 50 effective if it was discharged directly into the bed of fuel. Furthermore, actual experience has shown that the liners, or inner walls, of the old type of fire door are soon destroyed by the heat of the furnace, and the 55 dead plate forming a threshold for the fire door is likewise burned by the intense heat

of the furnace. It is therefore apparent that the draft passing through the ordinary fire doors does not effectively cool either the inner wall of the door or the dead plate. 60

In the preferred form of the invention, the fire door has an outer wall provided with an elongated horizontal draft inlet at its top margin, and the inner wall is separated from said outer wall to provide a down-duct for 65 all of the draft entering through said top margin. A discharge port for the draft is formed at the lower margin of the inner wall. The door is otherwise closed to prevent free admission or escape of draft at 70 any other points. All of the incoming draft must, therefore, pass downwardly along the inner wall of the door, so approximately the entire area of the inner wall is exposed to the cooling action of all of the draft. After 75 being preheated by passing from the top to the bottom of the inner wall, all of the draft, passing from the lower margin of the door, is forcibly discharged over the dead plate and directly into the bed of fuel. The draft 80 is thus utilized to cool the inside of the door and the dead plate, and then discharged into the fuel bed where it will commingle directly with the solid fuel undergoing combustion.

Fig. I is a vertical section of a portion of 85 a furnace, illustrating a fire door constructed in accordance with this invention.

Fig. II is a front elevation of the door and the frame whereby it is supported.

A designates the front wall of a furnace 90 provided with a fuel-receiving opening 1 adjacent to a grate 2, on which the fuel is supported. 3 designates the dead plate at the bottom of the opening 1.

A door frame B, secured to the front wall 95 of the furnace, extends around the opening 1, said door frame having a wide top flange 4, a narrow bottom flange 5 and side flanges 6 provided with inclined edges which extend from the top flange to the bottom flange. 100 Inclined ribs 7 are formed on the side flanges to limit the outward movement of the fire door.

The door I have shown to illustrate the preferred form of the invention comprises a 105 rectangular outer wall 8 located between the side flanges 6 on the door frame and extending from the top flange 4 to the bottom flange 5, the upper edge of said outer wall 8 being in front of the top flange. The upper 110 portion of the outer wall is provided with an elongated horizontal draft inlet 9, which

extends approximately from one side of the door to the other. An inward wall or liner 10 is separated from the outer wall to form a down-duct 11 for the draft entering 5 through the inlet 9. The lower edge of the inner wall 10 is higher than the lower edge of the outer wall to form an elongated horizontal discharge port for the draft. The down-duct 11 and its discharge port extend 10 entirely across the interior of the door, said duct being open at the bottom to permit the incoming draft to pass freely from the bottom of the door.

A damper 12, pivoted at 13, is arranged 15 inside of the door to control the flow of air through the inlet port 9. 14 designates an operating handle pivoted to the damper and provided with teeth adapted to cooperate with an edge on the front wall 8 in securing 20 the damper in the position to which it is adjusted. A flat bar 15, secured to the inner face of the wall 8, has round extensions 16 at its ends forming trunnions whereby the door is pivotally supported, said trunnions being 25 mounted in bearings 17 on the stationary door frame. A counterweight 18 is secured to arms 19 fixed to the trunnions 16. When the parts occupy the positions shown in the drawings, the counterweight tends to retain 30 the door in its closed position.

The means for connecting the inner wall 10 of the fire door to the outer wall, preferably includes bolts 20 having heads 21, which lie in pockets formed at the ends of separating lugs 22 on the inner wall 10. These lugs separate the inner wall from the outer wall.

To prevent undue heating of the bolt heads 21 which lie adjacent to the fire, very 40 small holes 23 may be drilled through the lugs 22 on the inner wall 10. These restricted holes or ports allow a very small proportion of the draft to escape at the bolt heads 21, but the leakage is so slight that it 45 does not materially impair the efficiency of the current of air escaping through the discharge opening at the lower edge of the inner wall 10.

All of the draft passing through the fire 50 door enters at the elongated inlet 9 and passes into the top of the down-duct 11, whereby it is conducted to the discharge opening at the lower edge of the inner wall. The draft is thus discharged over the dead plate 3, and it passes directly to the bed of fuel supported on the grate 2. It is an advantage to discharge the draft directly into the solid fuel on the grate. Another important advantage lies in the discharge of 55 all of the draft onto the dead plate 3, so as to maintain the latter in a relatively cool condition, thereby protecting it from the

destructive effects of the intense heat at the adjacent body of fuel. It is likewise important to prevent burning or destructive 65 heating of the inner wall 10 which forms part of the fire door, and this is accomplished by causing all of the draft to pass downwardly from the top to the bottom of the duct 11, thereby effectively cooling the 70 wall 10 and at the same time preheating the air before it reaches the fuel.

The fire door herein shown has an elongated down-duct connecting the draft inlet at the top to the discharge opening at the 75 bottom, but the walls of said door are otherwise closed to prevent admission of air below said inlet and to also prevent free escape of air above said discharge opening.

I claim:

1. A fire door having an outer wall provided with a draft inlet, an inner wall separated from said outer wall to provide a down-duct for the draft entering through said inlet, a discharge port for the draft 85 being formed at the lower margin of said inner wall, and fastening means whereby said inner wall is secured to said outer wall, the inner end of said fastening means being secured at said inner wall, and a restricted 90 outlet for the draft being formed in said inner wall at said inner end of the fastening means for the purpose set forth.

2. A fire door having an outer wall provided at its upper margin with an elongated 95 horizontal slot forming a draft inlet which extends approximately from one side of the door to the other, an inner wall separated from said outer wall to form a down-duct for the draft entering said draft inlet at the 100 upper margin, the lower edge of said inner wall being higher than the lower edge of said outer wall so as to form an elongated horizontal discharge port for the draft, the walls of the fire door being otherwise closed 105 to prevent the admission of air below said draft inlet and to also prevent free escape of air above said discharge port, spacing lugs between said inner and outer walls, imperforate fastening means extending 110 through said spacing lugs and inner and outer walls and securing them together, each of said lugs and the inner wall having restricted draft outlets formed therein whereby the fastening means are cooled, a damper 115 located between said walls and at said draft inlet to control the admission of air to said down-duct, a door frame, and a pivotal support located at the upper margins of said walls and connecting the same to said door 120 frame.

In testimony that I claim the foregoing I hereunto affix my signature.

FRANCIS W. DEAN.
